UNITED STATES PATENT OFFICE.

OTTO LANGE, OF CHICAGO, ILLINOIS.

REVOLVING TEETER.

Application filed September 24, 1925. Serial No. 58,244.

This invention relates to revolving teeters or see-saws and has for its object the production of such a teeter adapted not only for pleasure, but also for exercise. One of the 5 objects of the invention is to provide a revolving teeter that can be used indoors when it is desired to provide regular exercise or for mere pleasure purposes. Another object is to provide an apparatus that can be locked 10 against oscillating and can then be used merely as a merry-go-round. Another object is to provide means so that the users of the machine can operate it and thereby obtain desirable exercise.

15 Of the accompanying drawings Fig. 1 is an elevation of a see-saw which embodies the features of my invention; Fig. 2 is an elevation of the same at 90° to the elevation of Fig. 1; Fig. 3 is an enlarged cross section along the line 3—3 of Fig. 2; Fig. 4 is a vertical sectional view along the line 4—4 of Fig. 2; and Fig. 5 is an enlarged transverse sectional view along the line 5—5 of Fig. 2.

20 The apparatus comprises in general an ordinary see-saw board 10 which is pivotally mounted on a support 11 and is free to rotate around the support and also to be tilted as much as may be desired. In operation the 25 operators sit on the ends of the board in the usual manner and operate it as a see-saw by means of their feet, or in any other suitable manner. As a merry-go-round the board is operated by means of operating arms 12 30 fixed to levers 13. These levers pass through slots in the board 10 and are pivoted to the board in any suitable manner, such as by means of pins 14. The lower ends of the levers 13 are pivoted to the ends of a link 35 40, so that the two levers are constrained to operate in unison. Pivoted to one of 45 these levers is another link 16 which is adapted to coact with a ratchet wheel 17. This co-action is produced by means of a 50 pawl 18 which is pivotally associated with the inner end of the link 16. The ratchet wheel 17 is fixed to the support 11 and as the board 10 is rotatably mounted thereon it will be seen that operation forwardly and 55 backwardly of the arms 12 will, by means of the connecting levers and links in conjunction with the ratchet wheel, force the board to rotate.

The support 11 comprises legs 25 fixed to 55 a sleeve 26. Within this sleeve is slidably

mounted a tube 27. Mounted on the upper end of the tube 27 is the ratchet wheel 17. Within the tube 27 is a rod 30 which rests upon the plate 28. Normally the plate 28 is supported by the cross piece 24; but if it 60 is desired to elevate the see-saw, the tube 27 together with the plate 28 are elevated until the hooks 29 pass under the plate and thus supports it a material distance above the floor. Rotation of the plate 28 is prevented by guide pieces 23 which are fixed to the piece 24. The hooks 29 are pivoted to the plates 43 which are fixed to legs 25.

65 By this arrangement it will be seen that the board 10, together with the frame 31, is 70 free to rotate with reference to the support, the frame being supported by the upper end of the rod 30, and being held in position by the tube 27 passing through an opening in the lower portion of the frame 31. 75

If it is desired to lock the board 10 so as to prevent oscillations thereof the following mechanism may be used. The flanges 33 are materially elongated and a plurality of holes 35 are provided therein. These flanges 80 are fixed to each side of the central portion of the board, and the pin 34 may be removed from one pair of holes in the flanges and the board shifted so as to place the pin in another pair of holes and thus to shift the 85 board longitudinally on the framework. Fixed to the framework is a bearing 38 in which is journaled a rod 39; and fixed to this rod are arms 40 having fingers 42 adapted to pass into certain of the holes 35 90 when the rod 39 is suitably turned. An arm 41, fixed to the rod 39, may be used for turning the rod so as to pass the fingers into the holes 35. When the mechanism is so arranged the board is locked and vertical oscillations thereof are prevented. If the board is to be moved longitudinally on the support it is unlocked and the fingers are placed in other holes in the flanges 33 on opposite sides of the hole through which the 100 pin 34 passes. In shifting the board longitudinally the pin 45 is removed and placed in one of the holes 46 in the link 16.

In order to assist in balancing the board 10 a weight 50 is mounted thereon for longitudinal movement. In this instance I prefer to slidably mount the weight 50 on a rod 51 which is fixed in any suitable manner to the board 10. Thus the board can be suitably balanced with reference to the relative 110

weight of the operators, and longitudinal shifting of the board may in this manner often be obviated. A thumb screw 52 is used for preventing sliding of the weight after it has been adjusted.

I claim as my invention:

1. A teeter comprising a support, a board mounted on said support for vertical oscillations and for horizontal rotations, and means for locking said board to prevent oscillations thereof, said means comprising a bearing mounted on said support, and a member journaled in said bearing, said member being adapted to coact with said board to prevent oscillations thereof when

said member is rotated to its locking position.

2. A teeter comprising a support, a rod rotatably mounted for vertical movement on said support, a board mounted on said rod for vertical oscillations and for longitudinal rotations, and means for elevating said rod with reference to said support, said means comprising a hook fixed to said support and adapted to support the lower end of said rod when it is elevated.

In testimony whereof, I hereunto set my hand.

OTTO LANGE.
